UNITED STATES PATENT OFFICE

GEORGE R. HOLMES, OF HENNESSEY, OKLAHOMA

SPORT TIMING CLOCK

Application filed April 4, 1929. Serial No. 332,517.

This invention relates to clocks and more particularly to clocks designed to be used for timing sports such as basket ball, foot ball, lacrosse and the like. In games of this character, the teams play for a certain definite length of time and if there is any stoppage of this play for any reason, time is taken out, these games usually having certain periods, as for instance quarters and halves. The general object of the present invention is to provide a large clock dial which may be observed by the spectators and which will have graduations thereon, the total graduations being equal to the total period of play and the dial being divided into the particular periods called for by the game to which the dial is to be applied, the clockwork having means whereby the timekeeper, whenever time is taken out, may stop the clock and start it again when play is rebegun so that the spectators may see for themselves just how much time is left of the playing period or periods, thus adding very greatly to the interest of the games as far as the spectators are concerned.

A further object is to provide a device of this character which is stopped or started electrically so that the timekeeper, umpire, referee or other proper party may readily control the clockwork from many different parts of the field or other observation point, permitting him to readily see just what is happening.

A further object is to provide means such that a relative large, long hand may be operated over a relatively large dial and stopped or started as before described.

Other objects will appear in the course of the following description.

My invention is illustrated in the accompanying drawings, wherein:

Figure 1 is a rear elevation of a clock constructed in accordance with my invention;

Figure 2 is a perspective view of the clutch shifter;

Figure 3 is a transverse sectional view through the clock;

Figure 4 is a face view of the dial;

Figure 5 is an elevation of the electro-mag-

net and the means associated therewith for shifting the clutch;

Referring to these drawings, 10 designates the frame of the clock which may be of any suitable construction or form. Mounted upon this frame are two driving gear wheels 11 each connected to a usual spring 12 whereby the gears may be driven, these springs and gears being preferably independent of each other.

Each of these gear wheels 11 engages with a pinion 13 mounted on the arbor of a gear wheel 14. Preferably, though I do not wish to be limited to this, the driving gear wheels 11 have eighty-four teeth, the pinions 13 have eight teeth and the gear wheels 14 are provided with sixty-six teeth. These gear wheels 14 mesh with a pinion 15 having twenty-six teeth. A train of gears of any suitable character, as for instance, the gear wheels 16 and 17 operatively drives a pinion 18 having for instance twelve teeth, this pinion being mounted upon an arbor carrying the escapement wheel 19. An ordinary escapement 20 is used in connection with this escapement wheel and is carried by the pendulum 46 in the usual manner. This pendulum carries upon it the weight 47 which is adjustable longitudinally upon the staff of the pendulum.

The gear wheel 15 is mounted loosely upon a central shaft 21. This shaft operatively carries the hand 22 which operates over the dial 23 of the clock. This hand is held in place by a nut 24. Mounted upon the shaft 21 is a sleeve 25 which has friction-tight engagement with the shaft 21. One end of this sleeve is squared for the reception of the square opening in the hand 22. When the nut 24 is secured in place, it not only holds the hand in place, but it forces the sleeve 25 down tight against a shoulder 26 which forms part of the shaft. This shoulder is chamfered or cut away at one end and the gear wheel 15 is counter bored to receive this cut-away end of the shoulder. Thus, it will be seen that the sleeve 25 turns at all times with the shaft 21 when this shaft is turned. The gear wheel 15 has on it twenty-six teeth. This gear wheel fits loosely on the shaft and

is entirely free to operate with relation to the shaft or with relation to the sleeve 25.

This wheel, it will be seen, as being constantly driven by the spring actuated gear wheels 11 and the train of gears transmitting motion to the gear wheel 15. On each side of the shaft 21, there is formed a flat key 27 and surrounding the shaft 21 and coacting with this key is a clutch member 28. Thus this clutch member is keyed to the shaft 21 and must turn therewith. Fitting over the opposite end of the shaft 21 from the sleeve 25 is a hollow, somewhat conical casing 29 and within this casing there is disposed a coiled compression spring 30 connected at one end to the clutch 28 and at its other end to the shaft 21. This spring urges the clutch into operative engagement with the gear wheel 15 and forces the gear wheel 15 against the shoulder 26 and thus under normal circumstances, the rotation of the gear wheel 15 causes the rotation of the shaft 21.

Coacting with the clutch 28 is a clutch shifting means comprising a transversely extending shaft 32 having adjacent one end thereof the fork 33, this fork embracing the clutch 28. At one end, this shaft 32, which is mounted in suitable bearings upon the frame 10 has an arm 34. Mounted in any suitable manner upon the clock supporting frame, is an electro-magnet 35, the coils of which are connected in a normally interrupted circuit with the source of current. The armature 36 of this magnet is mounted upon a rod 37 which may be made of bakelite or other insulating material and which is operatively connected to, as for instance by being pivoted, the arm 34. Thus it will be seen that when the electro-magnet 35 is energized, and the armature 36 drawn toward the magnet, the shaft 32 will be shifted to cause the clutch to be thrown away from the gear wheel 15 against the action of the spring 30.

However, as soon as the current through the magnet is cut off, the spring 30 will cause the clutch to engage the gear wheel 15 with the shaft 21. Any suitable switch may be used for closing the circuit through the electro-magnet and I have indicated such a switch as 38. This switch is illustrated entirely diagrammatically and may be of any suitable kind. While I have referred to an electro-magnet for actuating the clutch, I do not wish to be limited to this as a solenoid might be used, the core of the solenoid being connected to the rod 37. An angularly bent shaft 39 keeps the rod 37 and the armature in proper alignment with the electro-magnet.

It will be seen that the dial 23 is provided with a dial 40 and a second hand 41. This second hand may be driven in any suitable manner, but I have illustrated it as being driven by a train of four gears 42, 43, 44 and 45, the second hand 41 being mounted upon the arbor of the gear wheel 45. The gear

wheel 42 is mounted upon the sleeve 25 to rotate therewith. I have illustrated the dial 23 as being one adapted to be used in the game of basket ball as played at schools or by amateurs. The dial may be of any desired diameter as for instance three feet across, while the dial for the second hand is about six inches in diameter. The dial as used for playing basket ball at high schools and gradeless schools and under like circumstances is arranged to provide thirty-two minutes for playing time and, therefore, the minute hand instead of sweeping over sixty minutes in a complete revolution, sweeps through thirty-two minutes in a complete revolution and is marked to indicate the quarter periods.

In college basket ball, forty minutes is used for the game divided into twenty minute halves and, of course, the dial under those circumstances will be designed to indicate forty minutes and the minute hand will make a complete rotation around the dial in forty minutes. The total playing time of foot ball is sixty minutes divided into four quarters of fifteen minutes each and the dial under these circumstances would be correspondingly graduated. By having the dial with graduations corresponding to the total playing time of the game and having this dial large, the audience can see at all times just how the game is progressing and how much time is left in any period for play, and furthermore, there is no chance for either side to be cheated in time as the timer being operated by clock-work, is accurate. The same clock movement may be used for any of the timing clocks above referred to with just two changes in the size of the gear wheel 26 and the wheels 14. Of course, the gears that turn the second hand would have to be in proportion to the large hand.

In my construction the umpire, time keeper, referee or other official charged with this duty, would start the clock when play was started with the hand at the zero point on the dial and the second hand, of course, at zero. The hand would continue to move under the action of the clockwork unless something occurred which would require the stoppage of the game and time to be taken out. The official then closes the switch which retracts the clutch. The gear wheel 15 continues to operate, but the shaft or arbor 21 is held from operation or ceases its movement as does the pointer or hand on the dial. As soon as the ball is put into play again or the play is resumed, the switch is opened and the clutch engages the gear wheel 15 with the arbor and the pointer again moves over the dial.

While I have illustrated a certain definite construction which I believe to be particularly valuable, I do not wish to be limited to this as obviously many changes might be made without departing from the spirit of the invention as defined in the appended claims.

I claim:

1. A clock for timing sports having a relatively large dial, a balanced hand operating thereover, a shaft upon which the hand is mounted, a gear wheel for operating said shaft but rotatively mounted thereon, means normally connecting the gear wheel to the shaft, electrically operated, manually controlled means for releasing the connection between the gear wheel and the shaft, two trains of spring actuated gear wheels operatively engaging said gear wheel on the shaft to drive it, escapement mechanism driven from one of said trains and including a pendulum, and an escapement wheel.

2. A clock for timing sports having a relatively large dial, a shaft extending through the dial, a balanced hand mounted upon the shaft and revolving over the dial, a seconds dial, a hand moving thereover and operatively engaging with said shaft and driven thereby, a gear wheel associated with said shaft but loose thereon, a clutch associated with the shaft and gear wheel and resiliently shifted into a position to operatively engage the gear wheel with the shaft, an escapement wheel, a pendulum and an escapement mechanism associated with the pendulum and escapement wheel, a series of gears operatively engaged with the escapement wheel and including a spring actuated gear wheel, a second gear wheel associated therewith and engaging the gear wheel on the shaft at all times, and a second spring actuated gear train including a gear wheel meshing with the gear wheel on the shaft, and means for shifting the clutch including an electromagnet and armature associated therewith and operatively connected with the clutch, and a manually operable switch for closing the circuit through said electro-magnet.

In testimony whereof I hereunto affix my signature.

GEORGE R. HOLMES.
